COMBINED CARRIAGE AND FORMER FOR WIRE-BOUND-BOX MACHINES.

1,128,144.

Specification of Letters Patent.

Patented Feb. 9, 1915.

Application filed October 14, 1904. Serial No. 228,443.

To all whom it may concern:

Be it known that we, RICHARD G. INWOOD and PERRY C. LAVENBERG, citizens of the United States, residing at South Bend, in 5 the county of St. Joseph and State of Indiana, have invented new and useful Improvements in Combined Carriages and Formers for Wire-Bound-Box Machines, of which the following is a specification.

10 This invention relates to the manufacture of wirebound boxes and pertains more particularly to work-controlling means for determining or maintaining desired relative positions of different parts of box blanks or 15 blank sections preparatory to securing said parts together.

An object of the invention is to provide such work-controlling means for box blanks or sections of blanks formed of side sheet 20 material, separate or individual cleats, and binding wires.

The invention is hereinafter described, for 25 illustration, as embodied in a combined carriage and former arranged to hold in proper relative positions the side sheets and individual cleats for a sectional box blank in which provision is made for the overlapping of the edge of one side sheet by the margin of the next adjacent side sheet, at each lateral corner edge of the completed box. The 30 illustrative construction shown in the drawings comprises means for determining a desired overlap margin of the side sheet in a manner and for purposes hereinafter more 35 fully explained.

The carriage and former shown in the drawings may be used in conjunction with any practicable apparatus for securing together the wire binding and other parts of 40 blank sections. For instance a suitable machine for this purpose comprising a carriage and former such as that shown in the present drawings, is described and claimed in an application co-pending herewith, filed 45 October 27, 1904; Serial No. 230,249.

In the drawings: Figure 1 is a perspective view of the illustrative carriage and former. Fig. 2 is an enlarged perspective view showing a portion of the channeled bar and adjustable spacing block slidably mounted thereon. Fig. 3 is a transverse section on the line X-X of Fig. 2, showing the channeled bar, the divided spacing block and

means for clamping the latter to the bar. Fig. 4 is a perspective view of the bar and 55 spacing block mounted thereon, showing the adjustment of the separate block members relative to each other, so as to increase or decrease the intervening space between cleat ends as they are assembled on the carriage. 60 Fig. 5 shows a longitudinal sectional detail of one of the bars comprising the carriage, with cleats positioned thereon and spaced apart the desired distance by the adjustable spacing blocks. Fig. 6 is a perspective view 65 showing the members comprising a box blank assembled and positioned on the carriage and means for holding the sheets against displacement upon the cleats. Fig. 7 is a fragmental plan view of a cleat bar 70 showing a cleat in position between the spacing blocks and means for holding the cleat firmly in the cleat bar.

The combined carriage and former preferably comprises two longitudinal plates or 75 bars 1, which are connected and firmly held together parallel with each other, and at a distance apart corresponding to the length of the box sheets, or boards, by lengthwise adjustable cross bars 2, which are formed of 80 sections centrally slotted and held together by clamping thumb screws, allowing the bars 1 to be adjusted so as to increase or decrease the width of the carriage. The longitudinal bars or plates are provided with 85 dovetailed grooves 3, and side flanges 4, extending above the face of the bed plate 5, upon which the box cleats rest, the flanges 4 serving to position the cleats against lateral displacement. 90

A spacer or spacing block 6, comprising in the illustrative form two members 7, 7, is provided for maintaining adjacent cleats in their proper relative positions and as particularly illustrated in Fig. 5, maintains an 95 interval between adjacent cleats A, A, and projects upwardly between the cleat ends into engagement with the side sheets B, B. Thus where a spacer block occurs between the cleat ends, its upper portion serves, as 100 will be apparent from Fig. 5, as a gage by which the operator may position a side sheet B, B when he introduces the same to the carriage or former. The spacer block members 7, 7 have inclined face portions 8, which 105 terminate in extensions 9, 9 (Fig. 3), con-

forming with and connecting the dovetailed grooves 3, 3 of the bars 1, thus preventing vertical displacement of the spacing blocks but permitting movement of the blocks 5 lengthwise of the bars for adjustment of the spacing blocks to suit different lengths of cleats. The block members 7, when adjusted are locked against displacement by clamping screws 10, which draw the parts 10 together and clamp the extensions 9, to the bed plate 5, the said members normally sliding freely in said bed plate when not clamped thereto.

Referring to Fig. 5, it will be seen that 15 the spacing block 7 in the middle of the figure, co-operates with the similar block at the right of the figure to form a sort of pocket in which a cleat rests; and the upper portions of said two blocks, extending into engagement with the side sheet B, provide 20 gages by which the operator may position that side sheet B in relation to its cleat A. In other words, the two spacer blocks and the part connecting them, provide a former 25 or work holder for a side unit or section of the box.

Referring again to Fig. 5, it will be observed that each of the sheets B, B, has a margin which projects beyond the end of its 30 cleat. With this arrangement, as will be evident to those skilled in the art, when a binding wire is secured along the sheet, and the sections are then folded—for instance, by folding the section on the right of Fig. 35 5, in a clock-wise direction,—the edge of the right hand sheet B may be turned under the margin of the lefthand sheet B while the projecting margin of the right hand sheet B will be folded against the end of the 40 topmost step of the lefthand cleat A. Thus, when folded, as described, the projecting margin of the lefthand sheet B provides what we term an "overlap margin" by which one side sheet overlaps the other to 45 form a tight closure. It will also be readily apparent to those skilled in the art that the overlap margin of the right hand sheet B of Fig. 5 is provided to mate with the specific form of cleat used.

50 When the side sheets are positioned with their edges a distance apart less than the thickness of the side sheet (as shown in Fig. 5), and the wire bindings are secured to the sheets so positioned, the folding of 55 the blank, in which one sheet edge is forced under an adjacent overlap margin, puts the wires under heavy tension and holds them thus tensioned to maintain the overlapping sheets at the corner firmly held and tightly 60 closed. Thus it will be seen that the particular spacing blocks 6, in their application to the specific construction of box parts shown in the drawings, each performs two offices besides that of positioning adjacent 65 cleat ends in a cooperative foldable rela-

tionship: viz., to assist the operator in relatively positioning or gaging a cleat and side sheet to provide an overlap margin on one sheet of a width approximating the thickness of the sheet to be overlapped; and to 70 assist the operator in gaging or positioning the respective side sheets with their edges in proper relationship, *e. g.*, a distance apart not greater than the thickness of the overlapping sheet.

75 Since different thicknesses of sheets may require the cleat ends to be differently spaced apart for determining the overlap margin, the two sections 7, 7 of a spacing block 6, are made relatively adjustable by providing 80 one member of each block with a slot, 11, through which projects the clamping screw 10 the end portion only of said screw being threaded to engage a threaded tap in the adjoining member of the spacing block.

85 The members 7 are each approximately one-half the width of the bars 1 and therefore narrower than the cleats A. Thus by sliding the members upon each other to adjust them, and fastening them in adjusted 90 position, they may be caused to space apart adjacent step-mitered ends of the cleats, when the latter are placed in the bars, as required by the thickness of the lumber forming the sheet sections B.

95 In Fig. 2, the members 7 are shown in register whereby the cleats at their adjacent step-mitered ends are positioned close together, while in Fig. 4 the members are adjusted relatively to increase the space between the adjacent step-mitered ends of positioned cleats.

100 In order to hold the sheets against displacement upon the cleats as the carriage is passed through the stapling machines, two arms 12, are pivoted respectively to the end cross bars 2 at 13, and their free ends connected by a rod 14, which is swung over on to the sheets and rests thereon, the weight of the rod holding them, against displacement. See Fig. 6. As shown in Figs. 1 and 105 6, the arms 12 are pivoted to rock substantially in the planes of the adjacent edges of the side sheets B and consequently, as will appear to those skilled in the art, one or both 110 said arms will serve as a stop or stops to position the side sheet material in relation to the carriage and the cleats held by the spacers 6. When said arms 12 are located 115 as shown in Fig. 6 they stand in position to prevent any material movement of the side sheets lengthwise the cleats, while the stops 16 on the blocks 6 hold the side sheets against movement transversely of the cleats. Thus 120 all the parts are held in proper relations to be wired together to form a flexible wire-bound sectional blank. Since the sheets, as shown, in Fig. 5, may abut at their edges, the arms 12 may serve to hold all the sheets 125 properly positioned. It is convenient and 130

preferred, however, to have the additional gaging means provided by the upwardly projecting parts of the blocks 6 (Fig. 5).

In practice the spacers or spacing blocks 6 are adjusted on the cleat bars so as to conform to the width of the box to be manufactured, the length of the cleats determining the width of the box sides. This being accomplished the cleats A are positioned on the bars between the spacing blocks and the sheets B placed thereon so that the edges join or are quite close together, after which the retaining bar 14, is swung over so as to rest on the sheets, and hold them against displacement. This accomplished the carrier with its assembled box parts is passed through a stapling machine and the sheets stapled to the cleats over a stay or reinforcing wire, which holds the sections together when the blank is removed from the carrier. Fig. 6 also shows the stay wires C and the staples D which straddle said wires after which the carriage is withdrawn from the machine and the completed box blanks removed therefrom, and the same operation repeated. It is obvious that several carriages or groups of spacing and gaging devices, such as those described, may be introduced in succession to a single stapling machine so as to permit the box parts to be assembled upon one of said groups of parts while a preceding carriage or group is presenting its assembled box parts to a stapling mechanism.

In order to hold the cleats firmly in the channel and against the outer flange of the cleat bar, so that the cleats will register with the edges of the sheets, and to prevent wobbling of the cleats and possible displacement we provide plate springs 15, which are secured at one end to the inner flange of the bar or otherwise, and their free ends having engagement with said bar, the springs normally being distended or bulged in toward the center of bar, as shown in dotted lines Fig. 7. The spring being depressed as a cleat is inserted as indicated by full lines, thus firmly binding the cleat in position on the bar.

As will be apparent to those skilled in the art, this invention constitutes an important advance in the box making industry; especially in that it provides for the first time mechanical means for controlling side material and separate individual cleats (which may be made of cheap waste material) preparatory to applying binding wires thereto by which to form finished foldable wirebound box blanks or blank sections.

The invention is of course not limited to the specific construction, organization and mode of operation hereinbefore described for illustration.

What we claim as new and desire to secure by Letters Patent is—

1. Work-controlling means for use in as-

sembling box parts to be folded and secured together to form boxes, comprising, in combination, cleat-positioning means to receive a plurality of cleats disposed substantially end to end; and means relatively to position the adjacent ends of said cleats in co-operative foldable relationship. 70

2. Work-controlling means for use in assembling box parts to be folded and secured together to form boxes, comprising, in combination, cleat-positioning means to receive a plurality of rows of cleats disposed substantially end to end in the respective rows; and means relatively to position the adjacent ends of the cleats in each row in co-operative foldable relationship and to align transversely thereof the cleats in the respective rows. 75 80

3. Work-controlling means for use in assembling box parts to be folded and secured together to form boxes, comprising, in combination, cleat-positioning means to receive a plurality of cleats disposed substantially end to end; side-material positioning means; and means relatively to position the adjacent ends of said cleats in co-operative foldable relationship. 85 90

4. Work-controlling means for use in assembling box parts to be folded and secured together to form boxes, comprising, in combination, cleat-positioning means to receive a plurality of cleats disposed substantially end to end; and means, adjustable relatively to said positioning means, to be positioned at adjacent cleat ends—all constructed and arranged to position the cleats in a plurality of rows with adjacent cleat ends in each row in co-operative foldable relationship. 95 100

5. Work-controlling means for use in the manufacture of wirebound boxes, comprising, in combination, cleat-positioning means to receive a plurality of cleats disposed substantially end to end; and means relatively to position the adjacent ends of said cleats in co-operative foldable relationship, said last-named means being adjustable to suit cleats of different lengths. 105 110

6. Work-controlling means for use in the manufacture of wirebound boxes comprising, in combination, cleat-positioning means to receive a plurality of rows of cleats disposed substantially end to end; and cleat-spacing means relatively adjustable to suit individual cleats of different lengths to be received in said positioning means. 115 120

7. Work-controlling means for use in the manufacture of wirebound boxes comprising, in combination, cleat-positioning means to receive a plurality of rows of cleats disposed substantially end to end; and cleat spacing blocks adjustable relatively to each other and having relatively adjustable sections. 125

8. Work-controlling means for use in the manufacture of wirebound boxes comprising 130

ing, in combination, cleat-positioning means to receive a plurality of rows of cleats disposed substantially end to end; and cleat-spacing blocks having sections relatively adjustable to vary the spaces between the cleats.

9. Work-controlling means for use in assembling box parts to be folded and secured together to form boxes comprising, in combination, cleat-positioning means to receive a plurality of rows of cleats disposed substantially end to end; means for relatively adjusting said cleat positioning means in a direction transverse to the rows of cleats; and means relatively to position the adjacent cleat ends in coöperative foldable relationship.

10. Work-controlling means for use in assembling box parts to be folded and secured together to form boxes, comprising, in combination, mechanism for positioning cleats substantially end to end in a plurality of rows, and positioning adjacent cleat ends in coöperative foldable relationship; and means for relative adjustment of said mechanism, for positioning rows of cleats at different distances apart.

11. Work-controlling means for use in the manufacture of boxes comprising, in combination, cleat-positioning means to receive a succession of cleats; cleat spacing means to space endwise certain of said cleats; and means to clamp such cleats in position.

12. Work-controlling means for use in assembling box parts to be folded and secured together to form wire-bound boxes comprising, in combination, side-material and cleat-supporting members arranged side by side; means relatively to position adjacent cleat ends in coöperative foldable relationship; means for holding the side material in position; and means for holding the cleats in position.

13. Work-controlling means for use in assembling box parts to be folded and secured together to form boxes, comprising, in combination, cleat-positioning means to receive a succession of cleats; and means to predetermine successive spaces between the adjacent cleat ends to position said ends in coöperative foldable relationship.

14. Work-controlling means for use in assembling box parts to be folded and secured together to form boxes, comprising, in combination, cleat-positioning means to receive a succession of cleats; means to predetermine successive spaces between the adjacent cleat ends to position said ends in coöperative foldable relationship; and means to position side material relatively to the cleats.

15. Work-controlling means for use in assembling box parts to be folded and secured together to form boxes, comprising, in combination, cleat-positioning means to re-

ceive a plurality of cleats disposed substantially end to end; and means to be positioned between the ends of one cleat and the next to position said ends in coöperative foldable relationship.

16. Work-controlling means for use in assembling box parts to be folded and secured together to form boxes, comprising, in combination, cleat-positioning means to receive a plurality of cleats disposed substantially end to end; and means constructed and arranged to engage both of two adjacent cleats to maintain their adjacent ends in coöperative foldable relationship.

17. Work-controlling means for use in assembling box parts to be folded and secured together to form boxes, comprising, in combination, cleat-positioning means for a plurality of rows of cleats; and cleat spacing means to predetermine successive spaces between the adjacent ends of cleats in a row, said means being arranged to position said ends in coöperative foldable relationship and to space said ends apart a distance not substantially less than the thickness of side material to be used with said cleats.

18. Work-controlling means for use in assembling box parts to be folded and secured together to form boxes comprising, in combination, cleat-positioning means for a succession of cleats; and means to be positioned between the ends of one cleat and the next to position said ends in coöperative foldable relationship and to maintain between said ends a space not substantially less than the thickness of side material to be used with said cleats.

19. Work-controlling means for use in assembling box parts to be folded and secured together to form boxes comprising, in combination, cleat positioning means for a succession of cleats; and cleat spacing means to space apart the ends of one cleat and the next, a distance not substantially less than the thickness of the end of a cleat to be overlapped by side material, to position said ends in coöperative foldable relationship.

20. Work-controlling means for use in assembling box parts to be folded and secured together to form boxes, comprising, in combination, cleat-positioning means for a succession of cleats; and spacing means to space apart the ends of one cleat and the next, a distance not substantially less than the thickness of side material plus the thickness of a cleat end to be overlapped by side material, to position said ends in coöperative foldable relationship.

21. Work-controlling means for use in the manufacture of boxes comprising, in combination, cleat-positioning means to position individual cleats for a box side; and means to position side material relatively to said cleats to provide an overlap margin on at least one edge of said side material.

22. Work-controlling means for use in assembling box parts to be folded and secured together to form boxes comprising, in combination, cleat-positioning means for a succession of cleats; means to space cleats apart endwise a distance not substantially less than the thickness of the intended side material, to position said ends in coöperative foldable relationship; and gaging means at a cleat-interval by reference to which the corner line of the side material may be located in proper relation to said cleat interval.

23. Work-controlling means for use in assembling box parts to be folded and secured together to form boxes comprising, in combination, cleat-positioning means to receive a plurality of cleats disposed substantially end to end; means relatively to position the adjacent ends of said cleats in coöperative foldable relationship; and gaging means by reference to which the corner line of the side-material may be located to suit the foldable relationship of said cleat-ends.

24. Work-controlling means for use in assembling box parts to be folded and secured together to form boxes comprising, in combination, cleat-carrying means to receive a succession of cleats; and spacing means to be positioned between cleat ends to position said ends in coöperative foldable relationship and arranged to be carried with the cleats.

25. Work-controlling means for use in the manufacture of boxes comprising, in combination, two sets of cleat-positioning means arranged to hold a pair of cleats side by side, each set comprising means to hold a cleat against substantial endwise displacement, and side-material positioning means for relatively positioning the side material and cleats to provide an overlap margin on at least one edge of said material.

26. Work-controlling means for use in the manufacture of wirebound boxes comprising, cleat-positioning means for a succession of cleats; means to position longitudinally with respect to the cleats, side material extending over and upon such succession of cleats; and means acting upon a surface of the side material for maintaining the same in a proper plane relative to the cleats.

27. Work-controlling means for use in the manufacture of wirebound boxes comprising, in combination, a pair of cleat-positioning means side by side and each for a succession of cleats disposed substantially end to end; and a series of cleat spacing devices for each said positioning means, including means for an end cleat of a blank and one corresponding to each cleat interval, to position the end cleats of a blank and to position adjacent cleat ends in coöperative foldable relation, the spacing devices of one series being respectively aligned, transversely

of said cleats, with corresponding devices of the other series, to position cleats in transversely-aligned pairs for individual side sections of a box.

28. Work-controlling means for use in assembling box parts to be folded and secured together to form boxes, comprising, in combination, cleat-positioning means to receive a succession of cleats disposed substantially end to end; means relatively to position the adjacent cleat ends in coöperative foldable relationship; and means to position side material with at least one edge thereof in desired relation to certain of the cleats.

29. Work-controlling means for use in the manufacture of boxes comprising, in combination, cleat-positioning means to receive a succession of cleats disposed substantially end to end; means relatively to position adjacent cleat ends in coöperative foldable relation; and gaging means by reference to which corner lines of side material may be positioned in proper relation to the said cleat ends.

30. Work-controlling means for use in assembling box parts to be folded and secured together to form boxes comprising, in combination, a series of groups of positioning means, each group for a side section of a box, and comprising means to position a pair of cleats in transverse alignment and means to position sectional side material with at least one of its edges proximate the ends of said cleats; and said groups of positioning means being relatively arranged to position the ends of cleats of adjacent box sections in coöperative foldable relationship.

31. A former or work holder for positioning the parts of an individual side section for a sectional box, comprising, in combination, means to position a pair of individual cleats side by side and in transverse alignment; and means to position side material relatively to said cleats to provide an overlap margin on at least one side edge.

32. Work-controlling means for use in assembling box parts to be folded and secured together to form boxes, comprising, in combination, cleat-positioning apparatus, for a plurality of cleats disposed substantially end to end, constructed and arranged relatively to position adjacent cleat ends in coöperative foldable relationship; and gaging means by reference to which corner lines of side material may be positioned in proper relation to said cleat ends.

33. Work-controlling means for use in assembling box parts to be folded and secured together to form boxes, comprising, in combination, cleat-positioning apparatus for a plurality of cleats disposed substantially end to end, constructed and arranged relatively to position adjacent cleat ends in coöperative foldable relationship; and side-material positioning means.

34. In a work-controlling means for use in assembling a sectional box blank, a plurality of means for positioning respective box sections, the said means being relatively constructed and arranged to position their respective box sections in coöperative foldable relationship.
35. A work-controlling means for use in assembling the parts for a box blank comprising, in combination, cleat-positioning mechanism for a plurality of cleats disposed substantially end to end, constructed and arranged relatively to position the adjacent cleat ends in coöperative foldable relationship; and means relatively to position the edges of side material at opposite ends of the blank in coöperative foldable relationship.
36. A work-controlling means for use in assembling the parts for a box blank comprising, in combination, cleat-positioning mechanism for a plurality of cleats disposed substantially end to end, constructed and arranged relatively to position the adjacent cleat ends in coöperative foldable relationship; and means relatively to position the edges of side material at opposite ends of the blank to cause said edges to overlap when the blank is folded.
37. Work-controlling means for use in assembling box parts to be folded and secured together in making boxes, said parts including side material foldable along substantially parallel corner lines to provide box sides, and box members to be secured in pairs to said side material between and disposed transversely of corner lines thereof and near the extremities of said corner lines,—comprising, in combination, positioning means, to receive said members in pairs disposed substantially end to end, constructed and arranged to space one said pair from another a predetermined distance permitting said pairs to be foldably connected and folded into a predetermined relation in forming a box; and means to position side material relatively to said pairs of members to be foldable therewith.
38. Work-controlling means for use in assembling box parts to be folded and secured together in making boxes, comprising, in combination, cleat-positioning apparatus for a plurality of cleats disposed substantially end to end, constructed and arranged to space said cleats apart endwise a predetermined distance to permit them to be foldably connected and folded into a predetermined relationship in forming a box; and means to position side material extending over and upon said cleats and the spaces between them.
39. Work-controlling means for use in assembling box parts to be folded and secured together in making boxes, comprising, in combination, cleat-positioning means to receive a plurality of cleats disposed substantially end to end; and means to space endwise apart one said cleat for a given side of the box and another said cleat for a non-adjacent side of the box, a distance appropriate to dimensions of a desired intervening box slide.
40. Work-controlling means for use in assembling box parts to be folded and secured together in making boxes, said parts including side material foldable along substantially parallel corner lines to provide box sides, and box members to be secured in pairs to said side material between and disposed transversely of corner lines thereof and near the extremities of said corner lines—comprising, in combination, positioning means, to receive said members in pairs disposed substantially end to end, constructed and arranged to space one pair for one box side, from another pair for another and non-adjacent box side, a predetermined distance appropriate to intended dimensions of an intervening side, permitting said pairs to be foldably connected and folded into a predetermined non-adjacent relation in forming a box; and means to position side material relatively to said pairs of members to be foldable therewith.
